UNITED STATES PATENT OFFICE

FRANK J. HINDERLITER, OF TULSA, OKLAHOMA

ECCENTRIC SLIP SOCKET

Application filed October 22, 1928. Serial No. 314,062.

The present invention relates to fishing tools, and more particularly to a tool similar to the bit hook disclosed in my Patent No. 1,527,413, issued February 24th, 1925, and which I term an eccentric slip socket.

An object of my invention is to provide a fishing tool similar to my patented bit hook adapted to wedgingly engage the fish to be removed from the well.

10 Another object of the invention resides in the provision of an eccentric slip socket capable of contemporaneously moving a slanting tool in the bottom of the well to a vertical position and wedgingly engaging the tool at 15 an intermediate portion of the tool.

In my patented bit hook, a semi-circular shoulder was provided at the upper end of the cylindrical portion thereof, upon which the collar of the bit to be removed from the 20 well was designed to rest after the tool had moved the bit out of its slanting position into the vertical, so that when the tool was raised, the collar of the bit engaged the shoulder and the bit was removed with the tool.

25 Although my bit hook can be used satisfactorily to remove a bit from a well, as long as the collar end of the bit is accessible to the cylindrical portion of the bit hook, still I find that in some cases when the bit is inclined considerably out of the horizontal, it is desirable to wedgingly grip an intermediate portion of the bit rather than grip it at the collar. Therefore, the specific object of 30 this invention is to provide a slip socket similar in construction to that of my patented bit hook, but differing from the bit hook in that it includes wedge means whereby the socket may wedgingly engage an intermediate portion of the bit for the purpose of removing 35 the bit from the well.

Another object of the invention is to provide an eccentric slip socket having a tapered point merging into the hook portions carrying the slips whereby the tool may be aligned 45 with facility with the fish or bit and whereby the socket will not be apt to lodge on the top of the bit being recovered, but will tend to slide off the top of the bit into a proper engaging position.

50 In accordance with the general features of

my invention, I provide an eccentric slip socket comprising a substantially cylindrical tubular portion having its lower end cut on a slant and beveled upwardly on the inside to a plane disposed at right angles to the vertical axis of the tool and having one side formed open, there being slips on each side of the opening designed to engage the fish to be removed from the well. This eccentric slip socket of my invention, like my patented 60 bit hook, has an eccentric offset shank connected to the cylindrical portion at its lower end and having its upper end provided with a threaded pin for coupling with a string of fishing tubes or tools.

65 Other and further important objects of this invention will be apparent from the disclosures in the drawings and specification.

The invention (in a preferred form) is illustrated in the drawings and hereinafter 70 more fully described.

On the drawings:

Figure 1 is a fragmentary view partly in section illustrating the manner in which the slip socket of my invention engages a bit 75 hook in the bottom of a well.

Figure 2 is an elevation of the tool of my invention partly in section.

Figure 3 is a horizontal view partly in section taken on the line III—III of Figure 2 80 looking downwardly.

Figure 4 is an enlarged fragmentary sectional view of the lower end of my fishing tool taken at right angles to the illustration in Figure 2.

85

As shown on the drawings:

The reference character 10 designates the bottom of a well with a caved-in portion located at the place of drilling and designated by the reference character 11. Extending 90 downwardly in the well 10 is a string of pipes or fishing tools 12 including a bottom socket 13 into which is screwed a pin 14 formed integral with the collar 15 of a socket embodying the features of this invention. It is to be understood that the fishing tool of the present invention is lowered into the bottom of the well in the usual manner through the means of the string of pipes or fishing tools 13.

95

100

Extending downwardly from the coupling 15 is an offset shank 16 terminating at its lower end in a cylindrical portion 17. The cylindrical portion 17 comprises a pair of parallel hook members 18 extending laterally from the lower end of the shank 16 and being offset in an opposite direction from that of the offset shank 16. Incidentally, it is to be noted that the cylindrical portion 17 has a diameter approximating the inside diameter of the well or casing therein, so that when this portion reaches the cavein 11 in the bottom of the well, it will be carried farther out into this cavein by the tool swinging into the center of the casing as is obvious in Figure 1.

From Figure 3 it will be evident that the hooks 18 are formed by providing the cylindrical portion 17 with an open side. This open-sided cylindrical portion is so formed as to gradually taper from the lower points of the hooks to a meeting point or portion 20 in substantial alignment with the shank 16. In other words, the lower end of the cylindrical portion 17 is formed on a slant, the lowermost part of this end of the cylindrical portion being in direct alignment with the shank 16 of the tool. Also the lowermost point or portion 20 of the tool is disposed diametrically opposite the opening in the side of the cylindrical portion 17. This slant or taper on the bottom of the tool is important for the reason that it enables the tool to slide over the bit or other fish in the bottom of the well with facility. Moreover, in order to further insure this aligning action of the fishing tool with the bit or fish, the lower edges of the hooks 18 are drawn out to a more or less sharp edge as indicated at 21. The interior surface of the lower end of the cylindrical portion 17 is beveled as indicated at 22 upwardly to a horizontal plane disposed just below the wedges or slips 23 mounted in the cylindrical portion. That is to say, the entire inner surface of the cylindrical portion 17 at the lower end of the tool is beveled upwardly to a common plane for the purpose of facilitating the entry of the fish in the cylindrical portion between the diametrically opposite wedges 23-23.

The two wedges 23-23 are identical in construction and are positioned exactly opposite each other in the hooks 18 of the cylindrical portion 17. Each of these slips is mounted in a slot 24 having an upwardly and outwardly slanting bottom surface 25. The slots 24 are preferably of a dovetail construction so as to accommodate the dovetail slips 23 and to thus prevent lateral displacement of the slips. The slips are prevented from falling out of the slots in a direction lengthwise of the tool by the pins 26 and 27 disposed at opposite ends of the slots and suitably anchored to the hooks 18 of the cylindrical portion 17.

It will be noted from Figure 4 that a shoulder 30 is formed on the top of the cylindrical portion 17 by slightly recessing the shank 16. This shoulder is desirable since in the event the wedges or slips 23 should slip relative to the shank of the bit 31 (Figure 1) during the elevation of the tool in the well, the collar 32 will engage the shoulder 30 thereby permitting the fishing tool to continue the raising of the bit from the well.

It is thought that my novel method of fishing an object such as a bit or the like from a well will be obvious from a description of the operation of my novel fishing tool.

The operation of the fishing tool in my invention is briefly as follows: The tool is coupled to a string of pipe or other tools, such as those designated by the reference character 12 in Figure 1, and is thereafter lowered into the well 10 until the slanting end of the cylindrical portion 17 strikes an intermediate portion of the shank of the bit 31. In Figure 1 it will be noted that the bit 31 is lying in a position at an angle to the vertical due to the cavein 11. This means that the collar 32 or the coupling end of the bit is disposed out of alignment with the well 10. The pointed or slanting end 20 of the tool serves to prevent the end of the tool from lodging on the side of the shank of the bit and facilitates the engagement of the tool with the intermediate portion of the bit.

By rotating the fishing tool it is possible to align the opening in the side of the cylindrical portion 17 with the intermediate portion of the shank of the bit 31 whereby the bit is engaged by the slips or wedges 23. Obviously, due to the fact that the bit 31 is disposed in a slanting position the wedges or slips 23 do not completely engage the shank of the bit but have what may be termed a semi-pivotal engagement with the intermediate portion of the bit. Thereafter, upon an upward pull being exerted upon the fishing tool, the bit 31 will be swung out of its slanting position into a vertical one in line with the well hole 10, due to the fact that the fishing tool pivotally embraces an intermediate portion of the bit above its center of gravity. That is to say that I depend upon the weight of the bit itself to cause the bit to be swung into the vertical upon the exertion of an upward pull thereon. Obviously as the fishing tool is pulled upwardly the slips 23 are forced downwardly in their slots 24 into tight engagement with the sides of the shank of the bit 31 whereby the bit may be removed from the well with the fishing tool.

Now it is of course understood that many changes may be made in this invention and numerous details thereof may be varied through a wide range without deviating from the principles of the invention and therefore the invention is only to be limited in so far as

defined by the scope and spirit of the appended claims.

I claim as my invention:

1. In a fishing tool of the type described, a substantially cylindrical tubular portion having its lower end cut on a slant, said slanting end of said portion being beveled upwardly on the inside of the portion to a plane disposed at right angles to the vertical axis of the tool, an eccentrically disposed shank connected to said portion in line with the lowermost part of said slanting end, and a plurality of slips mounted in the inner surface of said cylindrical portion and arranged to engage with an intermediate portion of a slanting fish in the bottom of a well as the fishing tool is lowered on the fish.

2. In a fishing tool of the type described, an open-sided cylindrical tubular portion having its lower end cut on a slant, the opening in said portion being disposed opposite the lowermost part of said slanting end, said slanting end of said portion being beveled upwardly on the inside of the portion to a plane disposed at right angles to the vertical axis of the tool, wedge means mounted in said portion above said beveled end, and a shank connected to the other end of the portion for enabling the tool to be connected to a string of pipes or fishing tools, said wedge means being arranged to engage an intermediate portion of a slanting fish on the bottom of a well as the fish is lowered onto the same, whereby upon an upward pull being exerted upon the tool said wedge means will grip said fish in such a way that the fish, due to gravity, will be swung into the vertical.

3. In a fishing tool of the class described, a shank, an open-sided cylindrical portion on the end of said shank, said shank being offset relative to said portion and said portion being beveled to a point in line with said shank, and wedge means in said cylindrical portion on each side of the open side therein for facilitating the alignment of a fish with said portion and for wedging the fish to said portion.

4. In a fishing tool of the type described, a shank carrying means for attachment to a string of fishing pipe and the like, an offset tubular open-sided member formed from the material of the shank comprising oppositely disposed hook-like members merging into a depending point, and wedge means mounted in each of said hook-like members.

5. In a fishing tool of the type described, a shank carrying means for attachment to a string of fishing pipes and the like, an offset tubular open-sided member formed from the material of the shank comprising oppositely disposed hook-like members forming a flat semi-circular shoulder at the junction between the tubular member and the shank, said hook-like members merging into a de-

pending point, and a slip mounted in each hook-like member.

6. The method of fishing an object disposed in a position at an angle to the vertical in a well, which consists in engaging the object above its center of gravity, exerting a pull on the upper end of the object to cause the weight of the same to swing it from its angular position into the vertical and utilizing said pulling force to cause the object to be wedgingly engaged for elevation from the well.

7. The method of retrieving a bit or other fish from a well when the bit is disposed in a slanting position in the well, which consists in pivotally embracing an intermediate portion of the bit above the center of gravity of the bit, and exerting an upward pull on the bit to cause said bit or fish to swing from its slanting position back into the vertical whereby the intermediate portion of the bit may be wedgingly engaged for removal from the well.

8. In a fishing tool of the class described, a body including means for gripping the fish to be removed from a well and emergency means associated with said body and disposed above said gripping means for only engaging a portion of the fish in the event that the gripping means should fail to hold the fish.

9. In a fishing tool of the class described, a body including means for gripping the fish to be removed from a well and emergency means associated with said body for engaging a portion of the fish in the event that the gripping means should fail to hold the fish, said latter means comprising a shoulder formed on said body above said gripping means for abutting said portion of said fish.

10. In a fishing tool of the class described, a body including wedge means for frictionally engaging the fish to be removed from a well, and a shoulder formed on the upper end of the body above said wedge means arranged to engage a portion of the fish in the event that the wedge means should fail to hold the fish.

In testimony whereof I have hereunto subscribed my name at Tulsa, Tulsa County, Oklahoma.

FRANK J. HINDERLITER.
